PENDANT SCARECROW FIGURE

James H. Petter, North Bergen, N. J.

Application June 2, 1953, Serial No. 25,295

Term of patent 3½ years

(Cl. D35—1)

To all whom it may concern:

Be it known that I, James H. Petter, a citizen of the United States, residing at 8600 Boulevard East, North Bergen, New Jersey, have invented a new, original, and ornamental Design for a Pendant Scarecrow Figure, of which the following is a specification, reference being had to the accompanying drawing, forming part hereof:

Fig. 1 is a front elevational view, showing my new design;

Fig. 2 is a side elevational view thereof; and
Fig. 3 is a top plan view thereof.

The face opposite Fig. 1 is the same as that shown.

I claim:

The ornamental design for a pendant scarecrow figure, as shown.

JAMES H. PETTER.
